(57) **CLAIM**

The ornamental design for a prewired utility set for model railroad and other displays, as shown and described.

DESCRIPTION

FIG. 1 is a perspective view of a prewired utility set for model railroad and other displays of the present invention.

FIG. 2 is a right elevational view of the prewired utility set for model railroad and other displays of FIG. 1;

FIG. 3 is a left elevational view of the prewired utility set for model railroad and other displays of FIG. 1;

FIG. 4 is a rear elevational view of the prewired utility set for model railroad and other displays of FIG. 1;

FIG. 5 is a front elevational view of the prewired utility set for model railroad and other displays of FIG. 1;

FIG. 6 is a bottom plan view of the prewired utility set for model railroad and other displays of FIG. 1; and,

FIG. 7 is a top plan view of the prewired utility set for model railroad and other displays of FIG. 1.

The broken lines shown in the drawings represent portions of the article and form no part of the claimed design.

1 Claim, 5 Drawing Sheets
